METALLIC CHAIR

Filed Sept. 22, 1927

Inventor

WILLIAM S. FERRIS

By Arthur W. Helon
Attorney.

UNITED STATES PATENT OFFICE.

WILLIAM S. FERRIS, OF ELKHART, INDIANA.

METALLIC CHAIR.

Application filed September 22, 1927. Serial No. 221,164.

This invention relates to improvements in metallic chairs and especially to those of the swivelling type and it consists of the matters hereinafter described and more particularly 5 pointed out in the appended claim.

Among the objects of the invention is to provide a simple, strong and improved construction for the seat frame as well as a novel arrangement of parts for rigidly securing said frame to the seat post.

These objects of the invention as well as others, together with the many advantages thereof will more fully appear as I proceed with my specification.

15 In the drawings:

Fig. 1 is a vertical longitudinal section through the seat frame of a chair embodying my invention.

Fig. 2 is a top plan view thereof.

20 Fig. 3 is a detail vertical section on an enlarged scale through one side of the seat frame as taken on the line 3—3 of Fig. 1.

As illustrated and described herein, the improved construction is embodied in that 25 type of chair which has become known as a "correct posture" chair but as will be apparent, said construction may also be embodied in other types of chairs where the peculiar characteristics thereof makes it of 30 advantage to do so.

Referring now in detail to that embodiment of the invention illustrated in the accompanying drawings, the chair which is made substantially all of metal, includes a 35 supporting base 1 comprising a plurality of tubular metallic legs 2—2 the top ends of which are held in substantially closely grouped relation by top and bottom spiders 3 and 4 respectively, the bottom ends of said 40 legs being bent to provide that spread necessary for stability. Said bottom ends of said legs are provided with suitable casters 5 upon which the chair may be easily moved about.

45 In the top end of the standard and having suitable rotative bearing as well as vertical adjustment in said spiders 3 and 4 is a seat post 6 the top end of which is reduced in diameter and is threaded to form a relatively short threaded extension 7 connected to the post proper by a shoulder 8.

9 indicates as a whole the seat frame of the chair. Said frame which is rectangular in plan, is wider than it is deep and it consists of front and rear members 10 and 11 respectively and side members 12—12. Said

frame is made of angle bar stock with the vertical flange thereof facing upwardly from the horizontal flange which in turn faces inwardly.

60 Connecting the said front and rear members of the seat frame is a metallic plate 13 of a width somewhat less than that of said seat frame. Said plate includes a horizontally disposed mid-portion 14 and front and rear portions 15 and 16 respectively, inclined upwardly in opposite directions and at slightly different angles and said front and rear portions terminate in end flanges 15^a and 16^a respectively. Said flanges engage the underside of horizontal flanges of the frame members 10 and 11 and are secured thereto in any suitable manner, as for instance by spot welding. Disposed substantially centrally in said plate is a hole 17 75 of a size to permit the extension 7 of the post to pass therethrough. Before the seat frame is mounted on the post, I place a bottom clamping plate 18 upon the post shoulder 8 and then apply a top clamping plate 19 to said mid portion 14 of the plate 13 after which I apply a nut 20 to said threaded extension. When said nut 20 is drawn tight, the clamping plates securely clamp the plate 13 to the seat post 6. By reason of the different angular inclinations of the plate parts 15 and 16 respectively, the seat frame is 85 slightly pitched downwardly toward the rear.

90 Associated with the seat frame thus described is a seat member or cushion 21. Said seat member or cushion which is removable with respect to the seat frame, rests upon the horizontal flanges of the seat frame members 10, 11 and 12 respectively and is 95 confined against accidental displacement by the vertical flanges of the seat frame. Each side of the seat member or cushion is undercut at the bottom as indicated at 22 for a purpose later to appear.

100 Also associated with the seat frame is a suitable back rest arrangement which includes side arms 23—23 each of which is pivotally connected to the outside of the vertical flanges of the seat frame side members 12—12 by a screw 24 that passes from the inside of the flange through any one of a number of holes 25 therein and into a threaded hole in the inside of said arm. The top ends of the side arms are connected 110 together by a back rest bar 26 which carries a curved back rest member 27. The said

arms are each held in the desired angular position by a brace arm 28, the top end of which is bifurcated as at 29 to straddle and be pivotally connected to side arm as by a rivet 30. The bottom end of said brace arms are each pivotally connected to the outside of the vertical flanges of the side members of the seat frame by a suitable screw 31 from the inside of said flanges, which screw may be engaged in any one of a number of holes therefor in the bottom ends of each brace arm. The screws 24 and 31 are large headed ones and as they are disposed on the inside of the vertical flanges of the seat frame side members they engage and are concealed within the undercut portions 22 of the seat member or cushion 21 when the same is in place upon the seat frame. It is apparent from the foregoing description that the back rest may be adjusted forwardly or rearwardly as well as vertically to bring the back rest into that position most convenient for the occupant.

The chair is indeed strong and simple in construction and the seat frame is rigidly secured to the post through the agency of a minimum number of parts which may be quickly assembled.

While in describing my invention I have referred in detail to the form and arrangement of the various parts thereof, I do not wish to be limited thereto except as may be pointed out in the appended claim.

I claim as my invention:

In a chair, a rectangular seat frame comprising front, rear and side members made of angle bars having the horizontal flanges at the bottom and facing inwardly and with the vertical flanges facing upwardly, a back rest member associated with the seat frame and including a side arm and a brace arm associated with each side member of the seat frame on the outside thereof, headed screws extending through the vertical flanges of said side members from the inside thereof and into said side and brace arms, and a seat member removably seated on the horizontal flanges of said seat frame members, the side portions of said seat member being undercut to accommodate the heads of said screws.

In testimony whereof, I have hereunto set my hand, this 15th day of September, 1927.

WILLIAM S. FERRIS
